UNITED STATES PATENT OFFICE

CHARLES W. GREEN, OF ILION, NEW YORK, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Original application filed October 20, 1925, Serial No. 63,695. Divided and this application filed June 22, 1927. Serial No. 200,632.

This invention relates to improvements in the key construction of cash registers of the key-operated type.

This application is a division of the co-pending application of Charles W. Green, Ser. No. 63,695, filed Oct. 20, 1925, to which reference may be had for a more complete description of the cash register to which the present invention has been applied.

10 While the improvements set forth in this application are shown applied to a particular type of cash register illustrated in the parent application their utility is by no means limited to this specific embodiment.

15 The improvements are of such a nature that they may be applied in various modifications to many other kinds and principles of cash registers and accounting machines.

It is the main object of the present invention to provide a novel form of key latch and key releasing mechanism which is simple in construction and reliable in action.

According to the present invention, the 20 various operating keys, in their normal positions, are maintained somewhat below the key coupler so that an initial depression of any key will not cause any movement of the coupler. It is during this initial de-

30 pression of a key that it becomes latched to the key coupler without causing any movement of the latter. The obvious advantage of this construction is that it permits an easy touch for the latching of any desired

35 keys which may be selected for operation. In the normal operation of the machine, it is intended that the several keys which are to be operated for the entry of a particular item shall be latched to the key coupler suc-

40 cessively and singly, so that the operator may control the operation of the machine by the use of but a single finger of one hand. Thus, where a series of keys are to be depressed, to represent a particular form

45 of transaction made by a particular clerk for a given amount, involving dollars, dimes and cents, the five keys necessary to represent the transaction may be successively depressed to their latched positions, without

50 causing any movement of the coupler. The

fact that no movement of the key coupler is required up to this time insures a substantially uniform touch in the operation of all of the keys to be latched. In the past, wherever provision has been made in a key operated machine for a successive latching of keys to the key coupler, it has been necessary to raise the coupler by the initial operation of the first key depressed, with the result that a variable amount of touch has been required in the depression of a series of keys to represent a transaction. When the desired keys have been latched to the coupler the operation of the machine may be completed by the full depression of any one of the keys already partially depressed or by the full depression of the last key to be latched to the coupler.

Provisions have been made for the release of the keys which have been latched to the coupler during an operation of the machine so that these keys may be properly restored to their normal positions below the coupler. This release of the keys is effected entirely automatically and remains effective at the time the key coupler is restored to its normal position, so that a weighted bail extending across all of the keys may return to normal all those keys previously latched to the coupler.

In order that any error which may have been made in the partial depression of the keys may be corrected and the keys restored, without compelling a full operation of the machine, which would result in the entry of an erroneous record, a manually operable key releasing device is provided, and in accordance with the present invention this device may co-operate with certain portions of the automatic key releasing mechanism to effect a release of latched keys and a restoration of the parts to normal by the aid of the weighted bail. In this connection, interlocking means are also provided to prevent the misuse of the error key after the operating keys have been moved beyond coupling position.

In adapting the invention for the performance of the objects stated above, the latching mechanism, in the illustrative machine here-

in disclosed, has been mounted on a separate vertically movable frame, which is independent of the key coupler but is connected for a simultaneous movement by the latter. By the use of this construction the keys, when partially depressed, are latched to the vertically movable frame and when the operation of the machine is continued by the full depression of one of the keys all of the latched keys are held, not only by the special latches but also by the usual lip on the key coupler which enters a notch in the rear end of each of the depressed keys.

It is toward the end of the down stroke of the keys that they are released from the special latches on the vertically movable frame, due to divergence of the paths of movement of the ends of the keys and the latches and, on the return stroke of the keys, the latches are held out of active position so that it is merely by the engagement of the lip of the coupler with the notches of the keys that the latter are held in coupled position. When the coupler reaches its normal position the lip will have been fully withdrawn from the notches in the keys so that they may be fully restored by the weighted bail. It may be understood that the special latching mechanism preferably comprises a series of separately movable members, such as, bails, one of which is related to each group of keys; for example, one member may be associated with the clerk's keys, another with the transaction keys, another with the dollars amount keys, another with the dimes amount keys, etc. In connection with this form of latching mechanism, the present invention includes suitable connections for preventing a full operation of the machine until a key in one of the groups has been partially depressed. In the embodiment herein disclosed these connections co-operate with the latch member or bail associated with the clerk's group of keys so that a full operation of the machine is prevented until one of the clerk's keys has been partially depressed. This mechanism is so constructed, however, that no particular sequence of operation of the keys is compelled and it is immaterial whether the clerk's key is depressed prior to or after the depression of either the transaction or amount keys. This form of operation which compels the depression of a clerk's key before the machine is fully released for operation, is known as the "closed keyboard". In order that the machine may at times be operated on the "open keyboard" so that a depression of a clerk's key will not be compelled, a suitable manipulative device is provided, together with connections to the mechanism normally compelling the operation of a clerk's key. On proper adjustment of this manipulative means, therefore, the machine may be made to operate either on the "open" or "closed" keyboard.

The present machine also includes mechanism whereby the clerk's keys may select its corresponding totalizer for operation. As a result of the interlocking construction between the amount keys and the clerk's keys it is necessary to depress a clerk's key prior to the amount keys to select the totalizer which it is desired to operate for the entry of a particular item. This mode of operation is known as the "closed keyboard" operation, but when the machine is conditioned for the "open keyboard" operation, the operation of the amount keys alone will select the totalizer which is normally selected for operation. When it is desired to select the other totalizer for operation it is necessary to depress the appropriate clerk's key.

Reference will now be had to the figures of the drawings which, taken in connection with the detailed description which will follow, constitute a full disclosure of one form of the invention.

In the drawings:

Fig. 1 is an end view of the machine to which the present improvements are applied showing the arrangement of the operating keys, the totalizer selecting mechanism and a part of the improved mechanism by which the keys are latched to the key coupler for further operation.

Fig. 2 is a detail view in elevation of one of the elements comprising a portion of the totalizer engaging devices.

Fig. 3 is a top plan view of the machine showing the arrangement of the keys, the totalizing devices and the latching mechanism associated with the keys.

Figs. 4, 5, 6, 7 and 8 are detail views of certain portions of the key latching and releasing mechanism.

Fig. 9 is a detail back view in elevation of one of the key latching bails.

Fig. 10 is a sectional view taken to the left of the machine showing the control lever for controlling the clerk's and amount keys interlock.

The general construction and operation of the various features of the invention as embodied in the illustrative machine having been explained rather fully in the foregoing statement in the objects of the invention a detail description will now be given of the essential elements of the machine embodying the broad invention defined by the claims.

Keys and operating mechanism

The illustrative machine is of the key-operated type of cash register and is provided with the usual series of operating keys, including amount keys 20 (Figs. 1 and 3) and a number of special keys which will be later described.

The machine, as disclosed, is provided with 27 amounts keys (Fig. 3) for registering amounts from 1¢ to \$9.99, but obviously the

capacity of the machine and the designation of the amounts may be varied to suit the particular use to which the invention is put. The amount keys 20 are all mounted on a shaft 21 (Fig. 1) extending across the machine and the keys are normally maintained with their forward operating ends elevated by means of a weighted bail 22 extending across the tops of all the keys in rear of their pivots, the bail having a plurality of arms extending forwardly and pivoted about the key shaft 21. Depression of the forward end of any key will serve to elevate the weighted bail 22 and carry the upper surface of the latter substantially into engagement with the under cut-out surface of a key coupler 23. At the same time the upper surface 24 toward the rear end of the key will engage the under surface of a projecting lip 25 of the key coupler. Continued depression of the forward end of the key will then serve to elevate the key coupler 23 as well as the bail 22 and during this continued movement of the parts the lip 25 of the coupler will enter the notch 26 of the operated key.

The usual connections are provided from the key coupler to a main operating shaft within the machine, these connections comprising a double rack member 27 (Fig. 1) having sets of oppositely facing rack teeth adapted to alternately engage a pinion 28 (Fig. 3) mounted on a main operating shaft 29 (Fig. 1). As is well known in the art, the oscillation of the key coupler 23 by the depression and return of one or more of the operating keys will serve to produce a full rotation of the shaft 29.

Differential mechanism

40 Adjacent to each of the amount keys 20 and pivoted upon the key supporting shaft 21 is a cam plate 30 (Figs. 1 and 3), which is provided with an operating cam slot 31, the slots of the cam plates of a series being 45 graduated to effect an action of from 1 to 9 units, as will be explained. A suitable connection is provided between each key and its associated cam plate, which may be in the form of a pin 32 mounted in each key and 50 adapted to co-operate with a slot or notch in a forwardly extending arm of the plate. For each group of keys, such as the pennies group the dimes group and the dollars group, there is provided a segment frame comprising a 55 pair of forwardly extending arms 33, loosely mounted upon a transverse shaft 34. Between each pair of arms 33 and supported at its ends by the latter is a rod 35, which normally rests in the open end of the graduated cam slots of the series of cam plates 30 associated with the operating keys of a particular group.

Each of the segment frames is movable with its related operating segment 37 mounted on the shaft 34 and adapted to differential-

ly adjust item type carriers and to operate the totalizing devices. The segments 37 are nested (Fig. 3) while the segment frames extend transversely of the machine and to transmit movement from the frames to the segments any suitable cross connections may be used and since this mechanism is not involved in the present application it is not shown or described in the detail herein. One form which may be used is illustrated in the parent application above identified.

As the operating key of a particular group is depressed it will rock its associated cam plate 30 by means of the pin and slot connection 32 and this cam plate, through its cam slot 31, will engage the rod 35 and rock the segment frame related to the key depressed an amount depending upon the value of the cam slot. As the rod 35 is raised by one of the cam plates of a group, it will pass in front of the forward edge of the cam plates associated with the undepressed keys of the group. Rocking of the segment frame will, serve to rock the related actuating segment 37 in a counter-clockwise direction (Fig. 1) about the shaft 34. Upon release of the operated key after full depression, the parts described will return to their normal positions.

Totalizer selecting mechanism

The machine, as herein disclosed, is provided with a plurality of totalizers (two being shown) (Figs. 1 and 3) which are adapted to selectively receive and accumulate the several amounts entered into the machine. The machine is so constructed that both of the totalizers are normally out of engagement with the actuating segments, but one of them is adapted to be normally rocked into engagement with the segments, at the beginning of the down-stroke of the keys, while at the end of the down-stroke or the beginning of the return of the keys this totalizer is again disengaged from the actuating segments. Whenever it is desired to add an amount in the other totalizer, a clerk's or totalizer selecting key is operated and has the effect of causing the engagement with the actuators of the second or selected totalizer and preventing the engagement of the first mentioned totalizer. The preferred form of mechanism for accomplishing the above results will now be explained.

It will be noted that a pair of totalizer frames 38_A and 38_B are provided, and these will be hereinafter designated as "A" and "B" totalizers, respectively. Each totalizer is provided with a pair of supporting hubs 39 (Fig. 3) which are adapted to co-operate with a pair of studs 40 (Fig. 1), projecting from each of the pair of intermediate supporting frames 41 and 42. The totalizer frames 38_A and 38_B are each provided with totalizer wheel supporting shafts 43_A and 43_B

43_B respectively, on which is mounted a plurality of totalizer wheels 44. Adjacent each of the wheels of the totalizer, and secured to the latter is mounted a pinion 45, which is adapted, at times, to co-operate with the associated driving segment 37 for the purpose of rotating the related totalizer wheel to enter an item.

For the purpose of rocking the totalizers about their supporting studs 40 and in order to carry the pinions 45 into mesh with the actuating segments 37, a rockable and slideable plate 46, is provided (Figs. 1 and 3). This plate is pivoted at 47 to the upper end 15 of an arm 48 secured to a shaft 49. The rearward end of the plate is provided with a forked projection 50, adapted to co-operate with a pin 51 carried by a rock lever 52 pivoted at 53 to the intermediate frame 41. A 20 downwardly projecting extension of the rock lever carries a suitable pin or roller 54 adapted to co-operate with the raceway of a box cam 55, secured to the main operating shaft 29. This cam is so formed that during the 25 early part of the operation of the machine the rock arm will be lowered, while toward the beginning of the return stroke of the keys and the coupler the arm will be elevated to its normal position again. It will be obvious that rocking of the arm 52 will impart a rocking movement to the plate 46 first, in a downward or counter-clockwise direction and then upwardly in a clockwise direction. The upper rear corner of the plate 46 is provided with a square notch 56 which provides a rearwardly extending finger 57, which is adapted to engage the upper surface of the "A" totalizer wheel supporting shaft 43_A. Similarly, toward the forward upper edge 40 of the plate, a square notch 58 is provided and forms a finger 59 adapted to be brought over the upper surface of the forward totalizer wheel supporting shaft 43_B.

It will be noted that when the plate 46 is 45 in the position shown in Fig. 1 and the machine is operated to cause the arm 52 and the plate 46 to be rocked downwardly, the finger 57 will engage the "A" totalizer wheel supporting shaft 43_A and rock the pinions 45, carried by the latter, into engagement with the teeth of the actuating segments 37. However, if the plate 46 is shifted, in a manner to be described, slightly to the right of the position shown in Fig. 1, the finger 57 55 will be carried clear of the "A" totalizer supporting shaft 43_A, while the forward finger 59 will be carried over the "B" totalizer supporting shaft 43_B so that upon a subsequent downward rocking of the plate 46 about its 60 pivot 47, the "B" totalizer pinions 45 will be meshed with the actuating segments while the "A" totalizer pinions will not be shifted. Movement of the plate 46, to bring about the reversal of action of the fingers 57 and 65 59, is produced by shifting of the pivot 47

through rocking of the shaft 49 and the arm 48 against the action of a spring 60 which normally maintains the parts in the position shown in Fig. 1. Rocking of the shaft 49 is brought about by the operation of a clerk's or totalizer selecting key 61, which is designated "B" and which carries a pin 62 (Fig. 1) adapted to engage a cam surface 63 on a cam shoe 64 secured to the shaft 49. It will be noted that the cam shoe is so shaped that the initial depression of the key 61 will serve to rock the shaft 49, and hence move the plate 46, to cause the selection of the "B" totalizer and the disablement of the "A" totalizer. 75

Suitable mechanism is provided and associated with the plate 46 for preventing the rocking of one or the other, or both, of the totalizers, when they are not intended to be engaged with the actuating segments. The means, illustrated, for accomplishing this 80 purpose, as best shown in Fig. 2 comprises a detent plate 65 (Fig. 2) pivoted at 66 to the intermediate supporting frame 41. A suitable connection is provided between the plate 46 and the detent plate 65 which, as 85 shown, takes the form of a pin 67 extending from the plate 46 into cooperation with a slot 68 in the detent plate 65. In the normal position of the parts a detaining surface 69 of the detent plate is in engagement with the under surface of that "B" totalizer wheel supporting shaft 43_B, and thereby effectively prevents the rocking of the "B" totalizer frame during a normal operation of the machine. However, when the plate 46 is shifted forwardly, under the influence of a clerk's or totalizer selecting key 61, the surface 69 will be carried away from the shaft 43_B while, at the same time, a surface 70 of the plate 65 will be carried under the "A" totalizer wheel supporting shaft 43_A. Consequently, upon an operation of the machine in which the "B" clerk's key 61 has been depressed, the "A" totalizer will be positively 90 locked against rocking into engagement with the actuating segments, while rocking of the "B" totalizer frame will be permitted. 95

Key latching mechanism

As, has already been explained, the machine herein disclosed is provided with keys of several classes, including a plurality of groups of amount keys 20, a plurality of clerk's or totalizer selecting keys comprising the "B" key 61 and the "A" key 72 (Fig. 1) and a plurality of special transaction keys 73. All of these keys are maintained in their normal positions by the use of the special weighted bail 22, hereinbefore mentioned. It has already been explained that, in the operation of the machine, the selected keys may be partly depressed without affecting the key coupler, due to the fact that the latter is arrested at some distance above the 100 normal position of the keys by a pair of fixed 105

shoulders 74 (Fig. 1) which are formed on a pair of plates 75 located intermediate the side frames of the machine each having an aperture through which the key shaft 21 is passed and a notch 76 which engages a rod 77. A foot formed at the forward end of each plate rests on a base plate 78 while a rearwardly extending tail 79 of each plate is provided with a shoulder to engage the 10 raised ridge at the rear of the base plate 78. The upper edges of the plates follow the contour of the keys under the bail 22 while the lower edges of the plates follow quite closely the contour of the lower edges of the keys.

15 Provision has been made for the successive partial depression and latching of desired ones of the keys of each group, so that full depression of any one of the key may subsequently result in the complete operation of 20 all of the partially operated keys. The mechanism for accomplishing this result is, furthermore, so designed that the operation of a clerk's key may be compelled before a full operation of the machine may be effected. The construction is such, however, that no predetermined sequence of operation of 25 the keys is enforced. In order that the several keys may be partially depressed, as explained, and then carried by the key coupler 30 for a full operation, and also to prevent the depression of additional keys after the coupler has been shifted, it has been found desirable to provide the rear ends of each of the key levers with a compound surface adapted 35 to co-operate with the lip of the key coupler, the surface being composed of two arcs generated about two distinct centers. Taking the 40 amount keys, for example, as shown in Fig. 1, a surface 80, which is in an arc about the key shaft 21 as a center, is provided to permit the first partial depression of selected 45 keys, whereas the longer surface 81 which constitutes an arc about the center or pivotal point of the key coupler 23 is such that as the 50 coupler swings during an operation of the machine, it will not interfere with undepressed keys but will serve to prevent the depression of any additional keys after the coupler has commenced its movement. 55 It will be apparent that if a key was partially depressed and released it would be immediately restored to normal by the bail 22, if suitable means were not provided for holding it in partially depressed position. The 60 latching means, for preventing this return (Figs. 1 and 6) comprises a hooked extension 82 toward the rear end of each of the keys, which is adapted to co-operate with one of a series of bail members 83 pivoted about a 65 shaft 84 mounted in upwardly extending arms 711 of upright members or slides 710.

The pair of upright members 710 are slidably mounted in the rear framework 712 of the machine and are adapted to carry at their 70 upper ends portions of the indicating mecha-

nism, but since the latter is not involved in the present application the details of description are not given herein. For a complete showing and description thereof reference may be had to the parent application 75 #63,695, filed Oct. 20, 1925. The pair of right supporting slides 710 are provided with forked extensions 713 (Figs. 1 and 8) adapted to engage pins 714 carried by the extreme ends of the key coupler 23. Through the pin and slot connection as the key coupler rises the pair of slides 710 will be raised simultaneously and when the key coupler is restored to its normal position the slides will also be returned to their normal positions.

The number of bails 83 which are required depends upon the number of groups of keys, there being one bail for each group of amount keys, such as the dollars, dimes and cents groups, one bail for the clerk's keys and one bail for the special transaction keys. All of the bails 83 are normally urged in a counter-clockwise direction (Figs. 1, 4 and 6) by means of springs 85 extending between projections on the bails and projections on a pair 85 of separate retaining bails 86 secured to the shaft 84.

As is best shown in Fig. 1, whenever an amount key is depressed sufficiently to carry the rear upper surface 24 into engagement 90 with the lower surface of the key coupler lip 25, the hook 82 will first rock the bail 83, associated therewith, rearwardly until the shoulder of the hook is carried above the lower flange of the associated bail 83, at which time the bail is returned by the spring 85 to engage its flange under the hook, so that return of the key to its normal position will be prevented. Operation of a special transaction key 73 will result in substantially the 100 same latching action.

In order that depression of a clerk's key may be enforced, prior to any movement of the key coupler, the bail associated with the clerk's keys is of a slightly different form and differs slightly in its action. Attached to one end of the clerk's key bail 83 is a downwardly extending arm 89 (Fig. 5) carrying a pin 891, which is adapted to co-operate with a hook member 93 which is pivoted at 94 to a frame plate 941 secured to the underside of the base plate 78 (Figs. 4 and 5). A spring 95 attached to the hook member by a pin 930 and to the frame plate 941 by a pin 96 tends to rock the hook member until a rearwardly extending tail 931 engages the pin 96. When the machine is at rest a pivoted detent pawl 90, which is carried by the key coupler through a pivot pin 91 mounted on a plate 92, secured to the coupler, serves to hold the clerk's key latching bail rearwardly by the engagement of the surface 901 of the detent pawl with the lower overturned flange of the bail. When the bail is so held in rearward position the pin 891, carried by 110 115 120 125 130

its arm 89, engages under the shoulder 932 of the hook member 93.

A plurality of arms 88 (Figs. 3, 5 and 7) secured by some suitable means, such as pins, 5 to the shaft 84, are located between the several amount and transaction key bails and each has an overturned foot which engages over the lip of the key coupler, so that as the latter is rocked, during an operation of the 10 machine, its movement will be transmitted to the shaft 84. It will also be recalled that this shaft is carried by an extension of each of the slides 710, which are raised by the key coupler through the co-operation of the 15 forked ends 713 with the pins 714. It will be apparent, therefore, that when the hook member 93 is engaged over the pin 891 upward movement of the shaft 84 is prevented and the key coupler is locked against operation. 20 Each clerk's key 61 and 72 is provided with a laterally extending pin 512 (Figs. 4 and 5) which has its end in the plane of the detent pawl 90 to the rear of the pivot 91 of the latter, so that as any clerk's key is depressed 25 to engage its upper surface with the underside of the key coupler lip, the detent pawl will be rocked to carry its surface 901 above the lower over-turned flange of the clerk's bail 83. This rocking of the detent pawl 30 will permit the spring 85 to rock the clerk's key bail to engage the shoulder of the hook 82 of the depressed clerk's key and, at the same time to carry the pin 891 from under the shoulder 932 of the hook member 93, 35 with the result that the shaft 84, as well as the key coupler is now unlocked for operation.

The latch retaining bails 86, heretofore mentioned, are normally held against movement, independently of the rocking of shaft 84 by jaws 87 (Fig. 5) on a pair of the arms 88. The left hand one of these bails 86 (Fig. 5) furthermore, is provided with a finger 861 which serves both to limit the rocking of the 40 clerk's bail 83 under the influence of spring 85, when this bail is released by the pivoted pawl 90 and to aid in the restoration of this latch bail in a manner which will be described. A similar function is performed 45 with respect to the remaining bails 83 by the arms 88, each of which is formed with a flat rear surface 880 (Figs. 6, 7 and 9) which is adapted to co-operate with an extension 830 of the overturned flange of each of the adjacent bails 83. Thus, that arm 88 which is between the transaction and dollars groups key latching bails will normally arrest the forward swing of these bails, under the influence of springs 85, due to the engagement 50 of the flange extensions 830 of the bails with the rear edge 880 of the arm. So also the other arms 88 will serve to normally arrest the adjacent latch bails. The means where- 55 by the arms 88 and the finger 861 (Fig. 5)

serve to restore the bails 83 to key releasing position will now be described.

Secured toward the right hand end of the shaft 84 is a double lever 98, 99 (Fig. 8) which is normally rocked by a spring 100 until a pin 981 carried by the upper arm 98 engages a finger 715 extending upwardly from the forward arm 711 of the right hand slide 710. A shoulder 991 of the lower arm 99 of the double lever stands normally above an upwardly extending finger 1013 of a slide- 70 able and pivoted member 101 which has a slot 1012 surrounding the key shaft 21 and an enlarged opening 1011 surrounding a pin 131 extending from the right hand side of the weighted bail 22. In the normal position of the parts (shown by dotted out-line in Fig. 8) the pin 131 rests on the lower edge of the opening 1011 of the member 101 so that a shoulder 1010 formed at the rear of said member, normally rests upon the upper surface of the base plate 78. As the weighted bail 22 is rocked by the depression of an operating key and the pin 131 is raised (Fig. 8) a spring 102 attached to the forward end of the member 101, serves to rock the latter and tends to maintain the engagement between the lower edge of the opening 1011 and the pin 131. Rocking of the member 101, however, under the influence of spring 102, is limited by the engagement of the upper end of finger 1013 with the shoulder 991. Now, as the operation of the machine continues and the key coupler is elevated, the arm 99 and hence shoulder 991 will be raised in a vertical rectilinear path, whereas the upper end of finger 1013 will travel in an arc about the shaft 21 as a center. At some point in the upward movement of these parts the finger will become disengaged from the shoulder 991 and due to the action of spring 102, a slight extra amount of rocking movement will be imparted to the member 101. When the parts are returned toward normal the rearward surface of the finger 1013, being in engagement with the forward surface of the arm 99, will serve to rock the latter and the shaft 84 against the tension of spring 100, as the paths of movement of the finger and arm converge. Rocking of the shaft 84, as before explained, will result in the rocking of the arms 88 as well as the releasing bails 86, due to the clamping engagement of the jaws 87, so that the finger 861 and the rear edges 880 of the arms 88 will engage their respective bails 83 and rock the latter rearwardly to a gradually increasing extent to maintain the lower overturned flanges out of engagement with the hooks 82 of the latched keys. It will be understood that as the forward ends of the keys are depressed their rear hooked ends will travel away from the flanges of the bails 83 and the co-action between the finger 1013 and arm 99 is such as to entirely prevent the re- 110 115 120 125 130

engagement on the return stroke of the bails 83 and hooks 82, which became disengaged, due to divergence of path on the upstroke. As a result, the weighted bail 22 may continue the restoration of the keys to their normal positions without interference between the bails and hooked ends of the keys. The final movement of the bail 22, through the pin 131, will serve to restore the member 101, 5 likewise, to its normal position, in which the finger 1013 stands directly below the shoulder 991 of arm 99. It has already been mentioned that, during the entire movement of the coupler, all of the latched keys engage 10 their square notches 26 with the lip 25 of the coupler to maintain all of the depressed keys in coupled relation in the manner well known in the art, but this coupling action, 15 which is all that holds the keys in coupled 20 relation on the return stroke, of course, ceases upon return of the coupler to its normal position.

In order that the pin 891 carried by the 25 arm 89 integral with the clerk's key bail 83, may be properly restored to its normal position under the shoulder 932 of the hook 93, the latter is pivotally mounted, as explained before. The hook is, furthermore, provided with an upper cam surface 933 (Fig. 5) so 30 that even though the clerk's key bail 83 is rocked rearwardly, the pin 891 will not be blocked against movement but by co-operation with the cam surface 933 will merely rock the hook against the action of spring 35 95. Upon full restoration of the shaft 84, spring 95 will, of course, rock the hook to engage its shoulder over the pin 891.

Manual release of keys

40 Provision has been made, in accordance with the present invention, for the manual release of any keys which have become latched to the coupler, whenever it is desired to release them, without an operation of the 45 machine, due to some error. In providing this function, use has been made of the various elements, above mentioned, which are associated with the automatic release of the latched keys. This manually operable means 50 comprises a release key 105 (Fig. 3) which extends forwardly similar to the amount keys, the rear end of which is fastened to an arm 103 which is loosely pivoted on the shaft 49. The lower end of the arm 103 is provided 55 with a laterally extending finger which is adapted to co-operate with the curved forward end or finger 1014 of the member 101. Depression of the release key 105 will, therefore, cause the member 101 to be slid rearwardly on the shaft 21 and the finger 1013 of this member will engage the rear shoulder of arm 99 to rock the shaft 84, and hence all of the bails carried by the latter, to cause the 60 release of the latched keys.

65 For the purpose of preventing the opera-

tion of the release key, after the key coupler and the main rotation shaft have commenced their operation, a lug 104 is provided on one of the side frames of the machine (Fig. 8) 70 in a position to co-operate with the finger 1014 of the slide 101. It will be seen that when the slide is rocked by the action of the pin 131 upon the upper surface of the opening 1011, just at the commencement of movement of the key coupler, the finger 1014 will be carried in front of the lug 104 and thereby prevent rearward movement of the slide by the release key 105. The slight rocking of the slide by spring 102, upon the initial depression of a key, to carry the upper end of finger 1013 into engagement with the shoulder 991, however, is not prevented since this is prior to any movement of the coupler. As will be apparent, the lug 104 and finger 1014 serve, 75 also, to form a converse interlock, since, if the release key 105 is first depressed, the lower end of finger 1014 will be carried over the lug 104 and the opening 1011 of the slide acting on pin 131 of the weighted bail will prevent sufficient movement of the latter to rock 80 the key coupler.

Manual control of interlocking devices

The interlock previously described compels 90 the operation of either clerk's key 61 or 95 72 during each operation of the machine. This is known as the "closed keyboard". Sometimes it is desirable to operate the machine on the "open keyboard" arrangement which permits the operation of the machine without 100 requiring the depression of a clerk's key. In this instance depression of an amount key alone will permit the operation of the totalizer 38_A since the totalizer selecting mechanism is normally set to engage the "A" 105 totalizer with the actuating segments thus simplifying operations of the machine since in this case it is not necessary to depress the "A" key 72. However, to select totalizer 38_B 110 it is necessary to depress the "B" key 61.

For the purpose of determining whether the machine is to operate on the "open" or the "closed" keyboard the machine includes a control lever 316 (Fig. 10) pivoted about the segment shaft 34. The lever 316 may have 115 its upper end extending through a slot in the main casing of the machine, so that when a lid 8 is raised, this lever may be set in either of its two positions, indicated by the notches in the casing. At the lower end of the lower arm of the lever 316, is pivotally carried one end of a slide 318, whose rear end is slotted to permit sliding upon the stud 94 which supports the locking hook 93. A cam opening 3181 in the slide 318 is adapted to co-operate with a pin 934 which may be mounted in a forward extension of a modified form of the locking hook 93. When the lever 316 is in the position shown in Fig. 10 the pin 934 is 120 free to rise, vertically, in the forward end of 125 130

the opening 3181 so that the hook 93 may normally be rocked by the spring 95 to engage its shoulder 932 over the pin 891 to lock the key coupler against operation until a clerk's key has been latched and has permitted the clerk's key bail to rock forwardly. The pin 934, at this time, co-operating with the bottom of the opening 3181, serve to limit the rocking movement of the hook 93. At the same time, the vertical rise of the opening 3181, at this point, will permit the rocking of plate 93 counter-clockwise upon the return of the pin 891 toward the end of an operation of the coupler. Now, if the lever 316 is shifted to its upper position the slide 318 will be moved forwardly and the lower cam edge of the opening will positively rock the hook 93 to disengage its shoulder 932 from the pin 891. Obviously, when the hook is in this position, it will not be necessary to operate a clerk's key, to release the machine, and there results what is known as the "open keyboard" arrangement.

In describing the construction of the mechanism comprised by the improvement it has been necessary incidentally to give a thorough explanation of the operation of the different devices. It is thought, therefore, that the usual summary of the operation may in this case be omitted.

While the form of mechanism herein described is admirably adapted to fulfill the objects primarily stated, it is to be understood that it is not intended to confine the invention to the one form of embodiment herein shown, since it may be embodied in various forms, all coming within the scope of the claims which follow:

What is claimed is:—

1. In a machine of the class described, a plurality of operating keys, a common member operated by said keys after an initial movement of the latter, co-acting means on said common member and said keys for connecting the keys to the common member during movement of the latter, separate means for maintaining the keys in partially operated position, prior to any movement of the common member and means operated automatically during an operation of the keys for releasing said last mentioned holding means prior to the return of the common member to its normal position.

2. In a machine of the class described, a plurality of operating keys having an initial partial movement and a final full movement, a common member operated by said keys during the final movement of the latter, said keys and member having co-acting means for connecting the keys to the member during such final movement, separate latching means mounted for movement with the common member and adapted to hold the keys when given an initial partial movement, means for automatically releasing said sepa-

rate latching means during the operation of said common member, and means for restoring the keys to their normal position after said common member reaches its normal position.

3. In a machine of the class described, a plurality of operating keys, a key coupler normally spaced above the keys, a frame mounted for movement with the key coupler, means carried by said frame for retaining said keys when partially depressed, co-acting means on said coupler and said keys for connecting the latter to the coupler during further movement of the keys, means for releasing said key retaining means during the operation of the coupler, said releasing means remaining active when the coupler is returned to normal position, and means for restoring the keys to their normal position below the coupler.

4. In a machine of the class described, a plurality of rockable operating keys, a key coupler normally spaced above said operating keys, a vertically movable frame operated by said coupler, latching means carried by said frame to hold said keys when rocked into engagement with said coupler, means for locking said keys to the coupler upon movement of the latter, and means automatically operated by the movement of said frame for releasing said latching means, whereby said keys may be restored below said coupler on the return movement of the parts.

5. In a machine of the class described, a plurality of operating keys, a key coupler normally spaced above said keys, means for moving or restoring said keys to a position below said coupler, means for latching said keys when depressed sufficiently to engage said coupler, co-acting means on said coupler and keys for connecting the latter to the coupler when the coupler is moved from normal position, and means operated by said key restoring means for releasing said latch during the operation of the coupler, whereby said key restoring means may return the keys to normal position upon return of the coupler to its normal position.

6. In a machine of the class described, a plurality of operating keys, a key coupler normally spaced above said keys, means for moving or restoring said keys to a position below said coupler, means for latching said keys when sufficiently depressed to engage said coupler, co-acting means on said coupler and keys for connecting the latter to the coupler when the coupler is moved from normal position, a member operated by said key restoring means for releasing said latching means during the operation of the coupler, whereby said key restoring means may return the keys to normal position upon return of the coupler to its normal position, and manually operable means for operating said

latch releasing member independently of an operation of the coupler.

7. In a machine of the class described, a plurality of operating keys, a common operating member driven by said keys, means for latching one or more of said keys to said member prior to movement of the latter, manual means for releasing the latched keys, and means preventing operation of said manual means after said common member has commenced its movement.

8. In a machine of the class described, a plurality of operating keys, a key coupler common thereto, means for retaining said keys in partially operated position, manual means for releasing said keys prior to movement of said coupler, and means preventing operation of said coupler when said manual means is operated.

9. In a machine of the class described, a plurality of operating keys arranged in groups, said keys having an initial and a final movement of depression, a frame shiftable by the final movement of said keys, separate means carried by said frame for holding the keys of each group when given their initial movement, means controlled by the holding means for one group of keys to prevent an operation of the frame until a key of said group has been given its initial movement, and means operated during the movement of said frame to release all of said keys prior to the return of said frame to normal position.

10. In a machine of the class described, a plurality of keys arranged in groups, a common member operated by said keys, separate means for each of said groups of keys for latching the keys to said common member, and means controlled by the latching means for one of said groups of keys for preventing the operation of said common member.

11. In a machine of the class described, a plurality of keys arranged in groups, a common member operated by said keys, separate means for each of said groups of keys for latching the keys to said common member, means controlled by the latching means for one of said groups of keys for preventing the operation of said common member, and manual means for disabling said means for preventing the operation of the common member.

12. In a machine of the class described, a plurality of keys arranged in groups, a common operating mechanism driven by said keys, means normally compelling the operation of a key of one of said groups during each operation of said common operating means, and a normally inaccessible manipulative device for disabling said compelling means.

13. In a machine of the class described, a plurality of keys arranged in groups, said keys being capable of a partial and full oper-

ation, means normally preventing a full operation of the keys of a plurality of said groups, means controlled by the keys of another special group for disabling said preventing means, and a manipulative device for permitting the full depression of any of said keys without the depression of a key of said special group.

14. In a machine of the class described, a plurality of operating keys arranged in groups, a common operating member driven by said keys, means normally preventing the operation of said common operating means, connections from one of said groups of keys for disabling said preventing means, and a settable member independent of said groups of keys for disabling said preventing means.

15. In a machine of the class described, a key coupler, a plurality of oscillatable keys normally some distance below said coupler, any one of said keys being adapted to rock said coupler, means movable with said coupler for holding said keys when partially rocked into engagement with said coupler, said holding means, when said coupler is operated, being adapted to carry with it all of the keys thus partially depressed, and means for preventing the operation of said holding means upon return of the coupler to its normal position.

16. In a machine of the class described, a plurality of depressible operating keys arranged in groups, the keys in one of said groups being normally free for operation, and means compelling the operation of a key in said group, prior to the full depression of a key in any other group, said means permitting a partial depression of the keys in said other groups.

17. In a machine of the class described, a plurality of oscillatable keys having an initial and final movement in one direction, means for restoring the keys to normal position, means for retaining the keys in their initially moved positions, and means operated by said key restoring means for preventing the operation of said retaining means during the return stroke of said keys.

18. In a machine of the class described, a plurality of operating keys arranged in groups, a plurality of members universal to said operating keys of all of the groups and operated by the latter, means normally preventing the operation of one of said universal members but permitting the partial operation of the other, and means controlled by the keys of one of said groups for disabling said preventing means, whereby a key of any group may complete the operation of both of said universal members after a key of said one group has been operated.

19. In a machine of the class described, a plurality of operating keys mounted for movement about a fixed pivot, a key coupler normally spaced above said keys and adapt-

ed to be rocked by said keys about another pivot, a longitudinally movable frame operated by said coupler, co-acting means carried by said keys, coupler, and frame whereby 5 said keys are latched for movement with both said coupler and frame, said co-acting means between said frame and keys being disengaged by their divergent paths of movement, and means preventing the re-engagement of 10 said means on the return movement of said frame and keys.

20. In a machine of the class described, a plurality of pivoted operating keys, a longitudinally movable frame operated by any 15 of said keys, co-acting means carried by said frame and said keys whereby a plurality of the latter may be latched to said frame, said co-acting means between said frame and keys being disengaged during the operation of 20 said frame by the keys, and means preventing the re-engagement of said means on the return movement of said frame and keys.

21. In a machine of the class described, rockable operating keys, a frame adapted to be moved by said keys after an initial movement of the latter, means for latching said keys to said frame upon the initial movement of the keys, a pivoted and slid able member co-operating with said latching 25 means to release the latter upon movement of the frame, and a manipulative device for moving said pivoted and slid able member to release said keys independently of the movement of the frame.

22. In a machine of the class described, a plurality of oscillatable operating keys, a key coupler, a member for normally moving said keys to a position spaced below the coupler, means for latching the keys in engagement with the coupler, said means being mounted for movement with the coupler, means movable both with and independently of said member, and co-acting elements carried by said last mentioned means and said 40 latching means to retain the latter in released position upon return of the coupler to normal at the end of an oscillation, said member serving to restore said keys below the coupler 45 when so released.

23. In a machine of the class described, a plurality of depressible keys arranged in groups, a member common to and operated by said keys, separate means individual to each of said groups of keys for connecting 50 depressed keys to said common member, a second member common to said keys and operated by the latter and means operated by said second member for disabling the connection between said keys and said first 55 mentioned member.

24. In a machine of the class described, a plurality of keys arranged in groups, a plurality of totalizers, means under control of the keys of one group for selecting a totalizer 60 for operation, means controlled by the keys

of another group for operating the selected totalizer, a member common to said keys and operated by the latter, separate means for latching operated keys of each group to said common member, and means controlled by 70 the latching means for the keys of the first mentioned group for compelling the selection of a totalizer prior to the operation of the totalizer operating means.

25. In a machine of the class described, a totalizer, a plurality of groups of keys, means compelling an operation of all of said groups of keys for controlling the operation of said totalizer for accumulating items, and normally inaccessible means disabling said compelling means whereby operation of said totalizer is controlled for accumulating items by but one group of said keys.

26. In a machine of the class described, a plurality of totalizers, a plurality of groups of keys, one of said groups of keys being effective to select a desired totalizer for operation, means compelling an operation of both groups of keys for controlling the operation of the selected totalizer for accumulating items, and normally inaccessible means disabling said compelling means whereby operation of said totalizer is controlled for accumulating items by but one group of keys.
